COIN CONTROLLED MOVIE-SOUND
MACHINEJohn F. Eakins, Evanston, Ill., assignor, by mesne
assignments, to Phonovision Corporation, Chi-
cago, Ill., a corporation of Illinois

Application September 29, 1942, Serial No. 460,087

11 Claims. (CL 38—16.2)

This invention relates to coin controlled movie-sound machines and has for one of its principal objects to provide an improved, simple machine, whereby sound may be reproduced from records in synchronism with a projected movie film.

A further object of the invention is to provide an improved movie projector system which can readily be adapted for addition to selective automatic phonographs to provide a visual accompaniment for the sound reproduction.

In providing a visual reproducer to operate in synchronism with sound produced from phonograph records, considerable difficulty arises from the fact that phonograph records do not play for the same length of time, some playing longer than others. Furthermore, considerable difficulty arises in securing synchronism. When the needle hits a record, it cannot be predetermined what part of the spiral sound groove it will hit and the picture may be out of synchronism unless special means are provided for starting the film when the needle is at a definite position on the sound groove.

One of the objects of the invention is to provide an improved connecting system whereby the sound film starts to operate when the needle is at definite position on the sound groove.

A further object of the invention is to provide a movie selector which is correlated with the selector of the phonograph so that the proper visual recording is brought into operation when the sound record with which it is associated is played.

The present invention is described in connection with the well-known coin actuated Symphonola multi-selective phonograph many thousands of which have been manufactured and sold by J. P. Seeburg Corporation. This invention employs a multiple film in which a plurality of picture episodes are located on the same film. The film is broad enough to include several longitudinal rows of pictures, each row constituting a separate film episode.

Selector means are provided for bringing one row of pictures constituting one film episode into alignment with the projector and means are provided whereby the film selector is controlled by the selector of the phonograph. Since in that particular phonograph the selector moves continuously in one direction, the sound records are selected in the order 1, 2, 3 . . . 9, 10, 1, 2, 3, etc. Since the longitudinal rows of pictures on the film must be moved backward and forward, the correlation of the selectors presents a considerable problem because, to move from selec-

tion 10 to selection 1, it is necessary for the film to make a complete travel.

Another object of the invention is to provide a correlated selector system for the sound and visual records whereby it is insured that the proper visual record is brought into operation simultaneously with the corresponding sound record.

The invention will readily be understood from the following description of a preferred embodiment taken in conjunction with the accompanying drawings and with reference to the copending application of Marion R. Winkler, Serial No. 342,419, filed June 26, 1940, which shows a complete disclosure of the Symphonola phonograph, and in conjunction with my copending application Serial No. 460,086 filed September 29, 1942, which shows in detail a film and a projector adapted to cooperate therewith for the reproduction of any particular episode on the film.

Fig. 1 is a diagrammatic view of the mechanism of the present invention, including the principal wiring circuit;

Fig. 2 is a wiring diagram of the selector and coin control means whereby the controlling pins 62 of Fig. 1 are actuated into selecting positions; and

Fig. 3 is a sectional view, showing the moving picture mechanism of the machine located inside a cabinet.

Fig. 1 discloses only that portion of the Winkler application which it is necessary to modify for the purpose of the present invention. The reference numeral 88 designates a transformer which is connected to the power lines 10 and 11. One end of the secondary of the transformer 88 is grounded. The other end of the secondary is connected to a relay 87 which includes the motor switch 88. When the relay 87 is energized, the phonograph motor is put into operation.

The relay 87 is grounded by a switch 41 or by engagement of an actuated grounded pin 62 into a position where it engages a contact 83. As will be readily understood from the Winkler application, there is a sufficient number of the pins 62 to correspond one to each of the recordings desired to be reproduced. The Winkler application discloses a switch 225 which is adapted to energize a solenoid 88 which effects the return of the pin 62.

Fig. 2 discloses selector means whereby any desired number of pins 62 corresponding to any desired selections may be paid for and the pins selected or projected. A rotary shaft 43 driven by the selector of the mechanism of the phono-

graph carries an abutment 61 which is adapted to engage any one of the selected pins 62 so as to terminate the motion of the shaft 43, the position of which shaft determines which phonograph record will be played.

The solenoid 63 is carried by the shaft 43 so as to be brought into alignment with the arresting pin 62 and when the solenoid 63 is energized, the arresting pin 62 is returned to its normal position.

The switch 225 is arranged to close momentarily just before the selected record is moved out towards the turntable. The switch 41 is normally closed, but is arranged to open after the playing of a record and just after the record changing mechanism starts to move to return a played record to the magazine.

It will thus be seen that when any pin 62 is projected, the phonograph motor is put into operation, this motor having been arrested by the opening of the switch 41. The movement of the record changing mechanism by the operating motor of the phonograph, closes the switch 41 so that the phonograph continues to operate until the selector record has been played and until it starts to move back to the magazine whereupon the switch 41 opens. Consequently, the phonograph motor operates until the last selected record has been played. When the switch 41 opens and no pin 62 is in projected condition the phonograph motor ceases to operate.

To adapt the Symphonola phonograph of the Winkler application for the present invention, I provide a normally open switch 12 adjacent the switch 41 so that it is closed when the switch 41 is opened. One side of the switch 12 is connected to the power line 10. The other side is connected to a relay 13 which is arranged, when energized, to open a switch 14 in the circuit of the motor relay 97. The other side of the relay 13 is connected to one pole or leaf of a switch 15 of a lockup relay 16.

In series with the solenoid 63 I provide two lockup relays 17 and 18. When the relay 17 is energized, the lockup relay 17 opens and locks open a switch 19 which is also in the circuit of the motor relay 97. The lockup relay 18, when energized, closes and locks closed a switch 20.

Consequently, when the switch 225 is closed momentarily after a phonograph record has been selected and before that record has been played, the circuit of the motor relay 97 is opened and the phonograph motor stops until the lockup relay 17 is unlocked.

Upon the shaft 43 I provide a sprocket wheel 21 which is connected by means of a chain 22 to a sprocket wheel 23. The shaft of the sprocket wheel 23 carries a radial arm 24 which carries at its outer end a conductive pin 25. The sprockets 21 and 23 are of the same size so that the pin 25 attains a definite position for each selecting position of the shaft 43. Thus, if the shaft 43 is arrested by the engagement of its abutment 61 with the pin 62 corresponding to record number 7, then the pin 25 has an individual position on its circular path corresponding to record number 7.

I break one of the lines connecting the amplifier 216 to the voice coil of the loud speaker 229 and connect two lines 26 and 27 to the open ends. Across these two lines I connect a switch 28 on a lockup relay 29 and in parallel with the switch 28 I connect the unlocking winding 30 of the lockup relay 29.

One side of the main winding 31 of the lockup relay 29 is connected to the power line 11. The other side of the winding 31 is connected to the main winding of the lockup relay 16. The other side of this main winding is connected to the unlocking winding 32 of the lockup relay 18. The other side of the winding 32 is connected to a contact 33 which bears against the film 34 of the movie projector.

10 On the other side of the film I provide a contact 35 which is connected to the power line 10. The film is provided with an opening 36 which registers with the contacts 33 and 35 at the end of a projection of a film episode so that momentary engagement is established between the contacts 33 and 35, releasing the relay 18, locking up the relay 16 and locking up the relay 29. The momentum of the projector is sufficient to move the opening 36 clear of the contacts 33 and 35 so that the circuit is broken almost immediately.

15 The machine being intended for coin operation, I provide in the cabinet means for receiving from patrons coins of various denominations. Thus, as shown in Fig. 2, I provide a coin chute 53,

20 which may be intended for the reception of a dime. A dime falling through this coin chute momentarily closes a switch 54, which is in circuit with an electromagnet 55 located adjacent a ratchet wheel 56. The armature 51 of the mag-

25 net 55 carries a dog 58 adapted to move the ratchet wheel 56 one tooth from its normal position. In this normal position, a pin 59 carried by the ratchet wheel holds open a switch 60; but when the ratchet wheel is moved one or more tooth spaces from its normal position, this switch becomes closed. A similar pin 64 on the other side of the ratchet wheel is arranged in normal position of the ratchet wheel to open a switch 65; but when the ratchet wheel is moved one or 30 more tooth spaces from its normal position, the switch 65 is closed.

35 Of course, other coin chutes may be provided for the reception of coins of other denominations.

40 Thus, I may provide another coin chute 66 for the reception of a fifty cent piece, and in the fifty cent piece coin chute I may provide five switches 67, all of which are connected to operate the magnet 55 so that the ratchet wheel 56 is displaced 45 five tooth spaces by the insertion of a fifty cent piece.

50 The magazine switch constituted by the ratchet wheel 56 and the switch 60 limits the number of 55 selections which can be made, since, as herein-after pointed out, selections can be made only when the switch 60 is closed, and each selection effects return of the ratchet wheel 56 one tooth space towards its normal position.

55 Selections are made by a plurality of buttons 68, each of which corresponds to one particular selection. The buttons are pushed outwardly towards normal position by means of springs 69. Each button carries a bridging contact 70, which is normally located between a relatively large 60 stationary contact 71 and a relatively small stationary contact 72. Adjacent contacts 71 and 72 are connected together by conductors 73, and one end of the series constituted by contacts 70, 71, 72, and conductors 73 is connected to one power line 11.

70 When a button 68 is pressed inwardly, the movable contact 70 clears the contact 72. Consequently, if the patron tries to press two buttons 68 simultaneously, separation of one pair of contacts 75 70 and 72 will prevent the supply of energy to

the stationary contact 71 associated with the other button. The contact 78 of the button 68 nearest the power line 11 connects the long contact 71 with a contact 74 so that the power line 11 is connected to the solenoid 75, which is individual to the controlling button 68 and is individual to the same selection. Solenoids 75 are arranged around the individual selector pins 62, the arrangement being such that when one of the solenoids 75 is energized, the corresponding pin 62 is projected into the path of the arm 81. The button 68 also carries a movable contact 76, which is adapted to establish a circuit between two associated contacts 77 and 78. It is arranged so that this last-named circuit is established not later than the instant the contact 78 engages the contact 74, since the establishment of this circuit discharges credit from the ratchet wheel 56. All the contacts 77 are connected to power line 11, and all the contacts 78 are connected to a common line 79 which is connected to an electromagnet 80, similar to the electromagnet 55.

On the other side of electromagnet 80 it is connected to one side of a magnet 81, which is in turn connected to the other power line 10 through switch 60. The electromagnet 81 is similar to the electromagnet 55, but it is arranged so that it feeds the ratchet wheel 56 one tooth in the opposite direction, that is, towards its normal position, each time that the magnet 81 is energized. The electromagnet 80 is associated with a ratchet wheel 82 so that on each energization the ratchet wheel 82 is moved one step from its initial or normal position.

The ratchet wheel 82 carries a pin 84, which controls a switch 85. In the normal position of the ratchet wheel 82 this switch is open, and in all other positions it is closed. The switch 85 is arranged in parallel with the switch 65, both being connected to the power line 11. The other sides of the switches 65 and 85 are connected to the lamp projector. Consequently, the lamp is illuminated at all times during which either of the ratchet wheels 56 or 82 is displaced from their normal position. When both ratchets are returned to their normal position, the lamp is disconnected from the power supply.

It is to be noted that when there is credit on the ratchet wheel 56, selections can be made by energizing the appropriate solenoids 75, and each actuation of a button 68 to make such selections has the effect of moving the ratchet wheel 56 one step back towards its normal position and has the effect of moving the ratchet wheel 82 one step away from its normal position, thus transferring the credit from the ratchet wheel 56 to the ratchet wheel 82. The other sides of the solenoids 75 are connected to the side of the switch 60 adjacent the magnet 81. The circuit through any of the solenoids 75 cannot be completed unless the switch 60 is closed.

The projector mechanism may be substantially identical with that described in my copending application Serial No. 460,086 referred to above.

For the purposes of my invention, I prefer to provide a plurality of film episodes on a relatively large film 34, which in the specific embodiment shown is arranged for ten episodes. The film 34 is wide enough for ten frames 88, and each episode consists of one longitudinal series of frames. The frames may be about one-third of an inch wide; and in view of the relatively large size of film necessary, I prefer to provide at least one additional row of sprocket holes 87, in addition to the sprocket holes 88 along the edge of the film.

The mechanism is contained within a cabinet 89, as shown in Fig. 3, which cabinet is provided with a transparent screen 90 suitably of frosted glass, upon which the picture is projected. Light from the lantern 91 is projected through a frame of the film 34 onto a mirror 92, from which it is reflected upon a mirror 93, from which in turn it is again reflected onto the screen. A suitable lens structure 94 is provided on the outer side of the film 34 from the lantern 91 whereby the image is focused upon the screen 90. The film 34 is continuous; its ends being cemented together so as to constitute a relatively large loop. The excess film may be stored in any suitable manner. For example, it may be arranged on sprocket wheels 95 located behind the lantern 91 so that the major part of the film is located in vertical lengths in the manner shown in Fig. 3.

The film is fed from the sprockets 95 by means of feed sprockets 96 and cooperating rollers 100 through a frame 45, which is movably located between the lantern 91 and the lens structure 94 so that any particular row of frames of the film may be brought into alignment with the light emitting opening 44 of the lantern 91. The lantern 91 is provided with a rotatable shutter 101 whereby the light is interrupted in the necessary manner for movie reproduction.

The sprockets 95, 96 are driven continuously in appropriate directions by the motor 37 through a suitable gear reduction 102. The motor 37 and the phonograph motor are preferably synchronous motors so that the visual and tonal reproductions are maintained in synchronism. The lower sprocket 96 is driven by a shaft 103. The shaft 103 carries a worm 104, which meshes with the worm gear 105 rigidly mounted on the shaft carrying the sprocket 96.

Also mounted on the shaft 103 is a worm 106, 40 which drives a worm gear 107 rigidly mounted on a shaft 108, which extends through a claw housing 109 rigidly mounted on the structure 46, which carries the frame 45. The housing 109 carries three claws 110, which are arranged to enter the sprocket holes 87, 88 and effect the normal step by step movement of the film in usual movie projector fashion. The housing 109 contains the necessary mechanism for driving the claws from the shaft 108. This mechanism may be of any known or suitable type; and since many such mechanisms are in ordinary use in movie projectors, it is unnecessary to describe the same in detail.

The shaft 103 is driven by a worm 111, which 55 meshes with the worm gear 112, which is carried by the structure 46. The worm gear 112 is slidably mounted on a gear shaft 113, which extends from the gear reduction housing 102. The arrangement is such that the worm gear 112 is free to slide along the length of the shaft 113, while it is driven thereby in all of its positions.

The shafts carrying the upper sprockets 95 are provided with gears 114, which are operatively connected by idler gears 115. The forward gear 65 114 is driven by gear 116, which is rigidly connected to a worm gear 117. The worm gear 117 is driven by a worm 118 on a shaft 119 extending from the gear reduction 102.

Lower sprocket wheels 95 are provided with gear wheels 120. The two rearmost sprocket wheels 95 being driven in opposite directions, have their gear wheels 120 in mesh. The other lower sprockets 95 have their gear wheels 120 connected in series by intermediate idler gears 70 121.

The lower series of sprockets 95 is driven by gear 122 in mesh with idler gear 121 of the foremost of the lower sprocket wheels 95. The gear 122 has rigidly secured thereto a worm gear 123, which is in mesh with a worm 124 on the lower projecting end of the shaft 119. Since all the lower sprocket wheels 95, with the exception of the last one, have to rotate in a direction opposite to that of the upper sprockets 95, one of the worms 118 and 124 is a right hand worm, and the other is a left hand worm.

The shutter 101 is driven by suitable gearing 125 and a chain 126, which is driven directly from the shaft 119. The gear ratios are such that the shutter position is properly correlated to the claw mechanism. The film is sufficiently long to provide for suitable bights above and below the frame 45.

The upper sprocket 96 may suitably be driven by means of a worm 127 on a shaft 128 carried by the structure 46. The shaft 128 carries a worm 129, which is in mesh with a worm gear 130 also carried by the structure 46.

The gear 130 is slidably mounted relative to the gear shaft 131, which carries a gear 132, which may mesh with a suitable gear, for example the gear 116, to provide the necessary drive for the upper sprocket wheel 96, notwithstanding that the position of this sprocket wheel may vary.

The contact 33 is also connected to one side of an electromagnet 134 associated with the ratchet wheel 82 in the same manner as the electromagnet 81 is associated with the ratchet wheel 56. The other side of the electromagnet 134 is connected to the power line 11, and the arrangement is such that each time contacts 33 and 35 engage, that is, at the end of each reproduction, the ratchet wheel 82 is returned one step towards its initial position until at the end of all visual reproductions the switch 85 is opened and the illumination of the lantern 91 is terminated.

The projector is driven by the motor 37 and a selector motor 38 is provided for the proper location of the film. One side of the motor 37 is connected to power line 10. The other side of the motor 37 is connected to one side of a switch 39 which is connected to the side of the switch 15 which is connected to the relay 13.

The switches 28 and 39 are controlled by the lockup relay 39. When the relay 29 is locked up, switches 28 and 39 are open.

When the lockup relay 16 is locked up, the switch 20 is in series with the switch 40 so that the power line 11 is connected to a terminal 41' of a reversing switch 42 whereby power is supplied to the selector motor 38, this selector motor having its other side connected to the power line 10.

As is fully described in my copending application Serial No. 460,086, the motor 38 consequently operates to move the film 34 back and forward before the light emitting opening 44, the film 34 passing through a guide frame 45 which is carried by a structure 46. The structure 46 carries a rack 47 which is driven in one direction and the other by means of a pinion 48 driven by the motor 38 through suitable gear reduction 49.

The gear reduction 49 drives through bevel gears 50, a shaft 51 which carries an insulated arm 52 which is adapted to make contact with the pin 25. The arrangement is such that the arm 52 moves almost through one revolution in one direction and then through one revolution in the opposite direction when driven by the revers-

ing motor 38 so that the arm 52 may be brought into contact with the pin 25 no matter in what selected position the pin 25 may be. The movement of the carriage 46 is back and forward sufficient to bring each film episode into alignment with the light emitting opening.

The arm 52 is connected to the power line 10. The pin 25 is connected to the unlocking winding of the relay 17, which is connected through the 10 unlocking winding of the relay 16 to the power line 11.

The operation is as follows: When the machine is out of operation, no pins 62 are projected, switch 41 is open, and switches 14 and 19 are closed. Since the circuit of the motor relay 97 is deenergized, the phonograph motor is not in operation. The relay 18 is unlocked and the contacts 20 are opened and consequently no power is supplied to either motor 37 or 38.

20 The switches 60, 65 and 85 are open.

If the operator inserts a coin or coins into the coin chutes 53, 66, the credit ratchet wheel is moved a corresponding number of steps from its normal position, closing the switches 60, 65.

25 If the operator now makes his selection by depressing one of the buttons 68, the corresponding pin 62 is projected and at the same time the magnets 80, 81 are energized, moving the ratchet wheel 56 one step toward switch-opening position 30 and moving the ratchet wheel 82 one step away from switch-closing position. When switch 65 was closed, the projector lamp was illuminated, and the circuit is maintained by the closing of the switch 85 so that the lamp remains illuminated 35 until both ratchets 56 and 82 are returned to normal position. The final return of the ratchet 40 82 is effected by cooperation between the contacts 33 and 35, after all the visual reproductions paid for have been reproduced, which finally opens the lamp circuit. The projection of a pin 62 completes the circuit of the motor relay 97 so that the phonograph motor is put in operation immediately a button 68 is depressed. Immediately the phonograph motor starts operating switch 12 45 opens and the switch 41 closes. The closing of the switch 12 had no effect since its circuit was broken at the switch 20 and the switch 16 is locked up. The motor 38 does not operate because the switch 20 is open.

50 The operation of the phonograph motor moves the shaft 43 until its abutment 61 engages the projected pin 62 thus locating the phonograph selector for the moving out of the selected phonograph record for playing. Before the phonograph record is moved out, the switch 225 is closed 55 momentarily, returning the actuated pin 62 and locking up the relays 17 and 18.

The locking up of the relay 17 maintains the switch 19 open so that the phonograph motor relay 97 is deenergized and the phonograph motor stops.

60 The locking up of the relay 18 closes the switch 20 so that the motor 38 is put into operation to move the frame 45 in one direction and in the other, and likewise to move the arm 52 in one direction and the other until the arm 52 engages the contact 25 in its position corresponding to the phonograph record selected. This occurs when the frames constituting the corresponding film episode on the film 34 is in alignment with the light emitting opening 44 of the projector.

65 Engagement between the arm 52 and the contact 25 unlocks the relays 17 and 16. Consequently, the phonograph motor is put into opera- 70 75

tion to bring the selected record out onto the turntable and to start playing the selected record. The unlatching of the lockup relay 16 opens the circuit of the reversing motor 38 so that the film is no longer moved in one direction and in the other direction and the pictures constituting the corresponding film episode are in alignment with the light emitting opening 44.

The motor 37 is not put into operation immediately the relay 16 is unlocked because the switch 39 is open, the relay 29 being locked up. The switch 28 is open.

The unlocking winding 30 is arranged so that it requires a substantial current to effect unlocking of the relay 29. When the record starts to play, current is supplied to the voice coil, but this current is insufficient to actuate the winding 30. When, however, the music starts, the current through the winding 30 increases to an extent which results in the unlocking of the relay 29. Thereupon, the switch 39 is closed and the switch 28 is closed.

Consequently, the projector motor 37 starts to operate at an instant which is determined by the sound track on the record. The pictures constituting the film episode are located on the film in such relation that synchronization is obtained between the visual and sound records.

It will of course be understood that I may provide a special sound track on the record to give a suitable signal for starting the motor 37. Thus, at a definite position on the sound track of the record, there may be provided an initial section of wide amplitude, corresponding to inaudible sound, that is, sound of frequency above or below the range of the human ear. Such inaudible sound can readily be arranged to energize the winding 31 without the reproduction of a sound in the loud speaker 228 which can be heard by the listeners. I prefer, however, to employ the normal sound recording of music or other recorded material which is to be reproduced in the speaker 228 since in this way I avoid the necessity of special records.

The sound recording and the corresponding film episode are now reproduced in synchronism. Synchronism may readily be maintained by employing synchronous motors for the phonograph motor and for the projector motor 37.

Since sound recordings do not have exactly the same duration, I prefer to make the film 34 of such length so that it takes somewhat longer for the complete film to pass through its cycle than it does for the longest record which is to be played. The sound recording is therefore reproduced while the motor 37 is still operating and the record changing cycle of the phonograph goes into operation, opening the switch 41 when the sound record is starting to move back to the magazine. This breaks the circuit of the motor relay 97 and consequently the phonograph motor stops. At the same time the switch 12 is closed and the switch 14 is opened.

The motor 37 continues to operate until the contacts 33 and 35 come into engagement, whereupon the lockup relay 16 is unlocked, the relay 16 is locked up, conditioning the motor 38 for operation by closing the switch 40, and the relay 29 is locked up, opening switches 28 and 39.

The locking up of the relay 16 also breaks the circuit of the relay 13 so that the switch 14 closes. The momentary engagement between the contacts 33 and 35 also energizes the electromagnet 134 so that the ratchet wheel 82 is returned one

step toward switch-opening position. If only one visual and sound reproduction was paid for, the projector lamp is deenergized, and the whole machine ceases to operate.

5 If a plurality of selections have been made, that is, if a plurality of pins 62 have been projected and the ratchet wheel 82 has been moved a corresponding number of steps away from switch-opening position, the operation is the same. The phonograph motor stops operation when the switch 12 is closed, because the switch 14 is opened and remains opened until the contacts 20 are opened when the contacts 35 and 33 are brought into engagement at the end of a projecting operation. In this case the ratchet wheel 82 merely moves one step toward switch-opening position, but the switch 85 remains closed and the projector lamp remains illuminated. At the end of such operation, the circuit of the relay 13 is opened by the opening of the contacts 20 and when the switch 14 closes, the motor relay 97 is energized, its circuit being completed through closed switch 19, closed switch 14 and the engagement of one or more of the contacts 83 with one or more of the projected pins 62.

Consequently, the cycle of operations above described is repeated, selected records being reproduced by the phonograph and the corresponding film episodes being reproduced by the projector. When all the selections have been reproduced, no pins 62 are in projected condition and when the last film episode has been projected, the opening 36 establishes engagement between the contacts 33 and 35 with the result that the whole machine is put out of operation until further coins are inserted and further selections made.

30 Although my invention has been described in connection with specific details of a preferred embodiment thereof, it must be understood that such details are not intended to be limitative of the invention except in so far as set forth in the accompanying claims.

35 I claim:

40 1. In a combined automatic multi-selector phonograph and a selective movie projector arranged to reproduce synchronized audible and visible recordings, in combination, a circular array of movable selector members, means on said phonograph arranged to move into engagement with any actuated selector member whereby last said means is arrested, a contact operatively connected to last said means whereby said contact is arranged to occupy an individual position on arrestment of said phonograph means in any selected position, means for moving a multi-subject film to and from relative to the projector, contact means operatively connected to last said film moving means whereby last said contact means is moved to and fro in the path of the positions of first said contact, and means controlled by the engagement of said contact, and contact means for arresting the to and fro movement of said film.

45 2. In a combined automatic multi-selector phonograph and a selective movie projector arranged to reproduce synchronized audible and visible recordings, in combination, a circular array of movable selector members, manual selector means for effecting actuation of any plurality of said movable selector members, means on said phonograph arranged to move in one direction until it is arrested by any actuated selector member, thereby determining the sound record to be

reproduced, said selective movie projector being provided with a guide for a large film having a plurality of rows of pictures, each row being appropriate to one sound record in the phonograph, a reversing motor for moving said guide to and fro to move every row of pictures past the light emitting opening of the projector, a contact member driven by said reversing motor to and fro, a contact arranged to move by steps in the same direction and in step with said arrestable member, whereby said contact occupies any of a plurality of positions each corresponding to a recording, and means controlled by the engagement of said contact and contact member for stopping said reversible motor.

3. In a combined automatic multi-selector phonograph and a selective movie projector arranged to reproduce synchronized audible and visible recordings, in combination, a circular array of movable selector members, manual selector means for effecting actuation of any plurality of said movable selector members, means on said phonograph arranged to move in one direction until it is arrested by any actuated selector member, thereby determining the sound record to be reproduced, said selective movie projector being provided with a guide for a large film having a plurality of rows of pictures, each row being appropriate to one sound record in the phonograph, a reversing motor for moving said guide to and fro to move every row of pictures past the light emitting opening of the projector, a contact member driven by said reversing motor to and fro, a contact arranged to move by steps in the same direction and in step with said arrestable member, whereby said contact occupies any of a plurality of positions each corresponding to a recording, means controlled by the engagement of said contact and contact member for stopping said reversible motor, and means controlled by the sound record for initiating the operation of said projector.

4. In a combined automatic multi-selector phonograph and a selective movie projector arranged to reproduce synchronized audible and visible recordings, in combination, selector means adapted to initiate the operation of the phonograph motor and effect the selection of a sound record, means operated by the phonograph for arresting the phonograph motor before the record is played, a movie selector motor arranged to be put into operation by said phonograph operated means to locate a movie film in selective corresponding position, means driven by said motor for terminating its drive, for starting the phonograph motor and a movie projector motor arranged to be conditioned for operation by said movie selector motor, and amplifier control means for initiating the operation of the projector motor.

5. In a combined automatic multi-selector phonograph and a selective movie projector arranged to reproduce synchronized audible and visible recordings, in combination, selector means adapted to initiate the operation of the phonograph motor and effect the selection of a sound record, means operated by the phonograph for arresting the phonograph motor before the record is played, a movie selector motor arranged to be put into operation by said phonograph operated means to locate a movie film in selective corresponding position, means driven by said motor for terminating its drive, for starting the phonograph motor and a movie projector motor arranged to be conditioned for operation by said

movie selector motor, amplifier control means for initiating the operation of the projector motor, and film controlled means for terminating the operation of the projector motor and for conditioning the movie selector motor for operation.

6. In a combined automatic multi-selector phonograph and a selective movie projector arranged to reproduce synchronized audible and visible recordings, in combination, selector means adapted to initiate the operation of the phonograph motor and effect the selection of a sound record, means operated by the phonograph for arresting the phonograph motor before the record is played, a movie selector motor arranged to be put into operation by said phonograph operated means to locate a movie film in selective corresponding position, means driven by said motor for terminating its drive, for starting the phonograph motor and a movie projector motor arranged to be conditioned for operation by said movie selector motor, amplifier control means for initiating the operation of the projector motor, and means for automatically terminating the operation of the phonograph motor at the end of the playing of a record.

7. In a combined automatic multi-selector phonograph and a selective movie projector arranged to reproduce synchronized audible and visible recordings, in combination, selector means adapted to initiate the operation of the phonograph motor and effect the selection of a sound record, means operated by the phonograph for arresting the phonograph motor before the record is played, a movie selector motor arranged to be put into operation by said phonograph operated means to locate a movie film in selective corresponding position, means driven by said motor for terminating its drive, for starting the phonograph motor and a movie projector motor arranged to be conditioned for operation by said movie selector motor, amplifier control means for initiating the operation of the projector motor, means for automatically terminating the operation of the phonograph motor at the end of the playing of a record, and film controlled means for causing the phonograph motor to resume playing.

8. In a combined automatic multi-selector phonograph and a selective movie projector arranged to reproduce synchronized audible and visible recordings, in combination, a plurality of movable selector members adapted to put the phonograph into operation to effect the selection and playing of a corresponding series of sound recordings, a movie selector motor, a projector motor, means controlled by the phonograph selector for controlling the supply of power to last said motors and for interrupting the operation of the phonograph motor, switch means controlling the operation of the movie selector motor and the supply of power to the projector motor, movie selector means actuated by the movie selector motor to select a film corresponding to the selected sound record, means actuated by said movie selector for energizing the phonograph motor, for deenergizing the movie selector motor and for conditioning the projector motor for operation, and means responsive to the operation of the phonograph for initiating the operation of the projector motor so that its film is in synchronization with the sound record.

9. In a combined automatic multi-selector phonograph and a selective movie projector arranged to reproduce synchronized audible and visible recordings, in combination, a plurality of movable selector members adapted to put the

phonograph into operation to effect the selection and playing of a corresponding series of sound recordings, a movie selector motor, a projector motor, means controlled by the phonograph selector for controlling the supply of power to last said motors and for interrupting the operation of the phonograph motor, switch means controlling the operation of the movie selector motor and the supply of power to the projector motor, movie selector means actuated by the movie selector motor to select a film corresponding to the selected sound record, means actuated by said movie selector for energizing the phonograph motor, for deenergizing the movie selector motor and for conditioning the projector motor for operation, means responsive to the operation of the phonograph for initiating the operation of the projector motor so that its film is in synchronism with the sound record, and means controlled by the phonograph at the end of its sound reproduction for arresting the phonograph motor.

10. In a combined automatic multi-selector phonograph and a selective movie projector arranged to reproduce synchronized audible and visible recordings, in combination, a plurality of movable selector members adapted to put the phonograph into operation to effect the selection and playing of a corresponding series of sound recordings, a movie selector motor, a projector motor, means controlled by the phonograph selector for controlling the supply of power to last said motors and for interrupting the operation of the phonograph motor, switch means controlling the operation of the movie selector motor and the supply of power to the projector motor, movie selector means actuated by the movie selector motor to select a film corresponding to the selected sound record, means actuated by said movie selector for energizing the phonograph motor, for deenergizing the movie selector motor and for conditioning the projector motor for operation, means responsive to the operation of the phonograph for initiating the operation of the projector motor so that its film is in synchronism with the sound record, means controlled by the phonograph at the end of its sound reproduction for arresting the phonograph motor, and means controlled by the film at the end of its reproduction for interrupting the supply of energy to the movie selector motor and the projector motor, for conditioning the movie selector motor for operation, and for initiating the operation of the phonograph motor.

11. In a combined automatic multi-selector phonograph and a selective movie projector arranged to reproduce synchronized audible and visible recordings, in combination, a switch on said phonograph arranged to open momentarily at the end of the playing of a sound record, a second switch arranged to be closed momentarily when the first said switch is opened, a third switch

on said phonograph adapted to be closed momentarily after the phonograph makes each selection, a plurality of movable selector members each adapted when actuated to establish a circuit in parallel with the first said switch and through a motor controlled circuit, a fourth and fifth switch in said motor controlled circuit, each being adapted, when opened to terminate the operation of the phonograph motor, a phonograph selector adapted to be positioned by engagement with any actuated selector member, a movie selector member adapted to move with said phonograph selector member and to be arrested in definite positions corresponding to the actuated selector members, a movie selector motor adapted to move a movie film into any of a plurality of positions for reproduction of any of a plurality of film episodes, an arm driven by last said motor for engaging said movie selector member in any of its said positions, a first lockup relay in series with third said switch adapted to lock the fifth said switch open, a second lockup relay in series with first said lockup relay and electromagnetic means in series with said relay for returning the actuated selector members to initial position, a power switch on second said relay adapted to lock up a switch for the supply of energy to said movie selector motor and to the projector motor, a third lockup relay adapted when energized to connect last said switch to the movie selector motor and when unlocked to connect last said switch to contacts on a fourth lockup relay, second said switch being arranged to be connected to the power supply switch when the third lockup relay is unlocked, a relay in series with second said switch for effecting the opening of fourth said switch, the engagement of said arm and said contact being arranged to complete a circuit through the unlocking circuit of first said lockup relay and through the unlocking circuit of the third lockup relay, a film controlled circuit connected to the unlocking winding of second said relay, to the lockup winding of third said relay, and to the lockup winding of fourth said relay, and an amplifier controlled circuit connected to the unlocking winding of the fourth lockup relay, whereby the phonograph motor is put into operation to select a sound record and its operation is terminated before the playing of the record and simultaneously with the initiation of the movie selector motor and resumed after the movie selection is made, the operation of the movie selector motor is terminated and the projector motor is conditioned for operation, the projector motor is started, the phonograph motor is stopped after the sound record is reproduced, and the projector motor is stopped after projection of the film episode and the phonograph motor is conditioned for renewed operation.
